Primary Examiner — Jeffrey D Asch*Assistant Examiner* — Rebekah A Caruso(74) *Attorney, Agent, or Firm* — Davis Wright Tremaine LLP; Heather M. Colburn(57) **CLAIM**

The ornamental design for a mount for a portable device, as shown and described.

DESCRIPTION

FIG. 1 is a front perspective view of a mount for a portable device showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

Features shown in broken lines in FIGS. 1-8 are for illustrative purposes only and do not form part of the claimed design.
